ELECTRIC ORGAN

Sylvan K. Ketterman, Chicago, Ill., assignor to
 Gulbransen Company, Chicago, Ill., a corpora-
 tion of Illinois

Application February 17, 1941, Serial No. 379,197

8 Claims. (Cl. 84—339)

The present invention relates to electric organs, and particularly electrically operated reed organs.

The reeds are enclosed in an enclosed chest to which wind under pressure is supplied by a blower. The reeds are located in passages in the chests through which the wind passes on opening of valves controlling the passages. The valves are operated by electromagnets in circuit with the keyboard.

The electric circuit for operating the electromagnets comprises an essential feature of this invention.

A desirable feature of the invention is that a large tonal volume is obtainable, as well as a wide selection of volume and tone. Five complete sets of reeds are provided, each set being co-extensive in range with the keyboard. It is possible to play five notes with each key, one from each of the sets of reeds, and this whether a single key is played or more than one are played. This is a decided advantage over previous organs in which one key "borrowed" from another key for increased volume or number of notes, and, when the latter key was played, it had, in some instances, no effect as its corresponding note was already being sounded.

To add to the five notes that can be played from one key, another feature of the invention makes it possible to play an additional five notes an octave higher (or lower), making it possible to play ten notes with one key. Likewise, it is possible to play as many as fifty notes with one hand.

The keyboard is divided into an upper and lower register, and each register is provided with a separate set of stops for selection of the notes to be played. When like stops in the two registers are put into effect, the registers play in the respective sets of reeds in a continuous range. For a different effect, different stops in the two registers may be actuated, in which case the registers can be played in different ranges, e. g., one combination can be set up for the lower register and this played as an accompaniment for a solo melody part played on the upper register. This allows an extensive range for each hand approaching a two-manual effect with one actual manual. Another effect possible with this novel manual is that a two-manual ensemble can be played on the upper register while the pedal effect can be assimilated on the lower register.

Other objects and advantages of the invention will appear as the description of the invention proceeds.

In the drawings:

Figure 1 is a vertical sectional view through the organ of my invention;

Figure 2 is a view of the reed chest of the organ, taken on line 2—2 of Figure 1, but with the positions of the reeds and their valves and electromagnets shown schematically;

Figure 3 is a diagrammatic view of the reed chest, as viewed from the front, showing the relation of the reeds to the keys of the keyboard;

Figure 4 is a diagram of the circuit connecting the keys with the electromagnets associated with the reeds;

Figures 5 and 6 are top and side views, respectively, of the keys, showing the manner of completing the circuit through the keys, and the switching means operated by the keys;

Figure 7 is a plan view of the organ "stops," i. e., switch levers for selecting the various reeds in playing;

Figure 8 is a view taken on line 8—8 of Figure 7 showing the stops or switches;

Figure 9 is a view taken on line 9—9 of Figure 7 showing the "full organ" stop or switch;

Figure 10 is a view of a valve for controlling the admission of wind to a reed, and the electromagnet for operating the valve;

Figure 11 is a view of a relay for controlling additional electromagnets;

Figure 12 is a view from the right of Figure 11; and

Figure 13 is a top view of a portion of the switch used with the relay of Figure 11.

Referring in detail to the drawings, the organ comprises a cabinet 1, with a keyboard, indicated generally at 2, supported in the usual position on a base 4 extending transversely of the cabinet and secured to the ends thereof. The individual keys 3 are supported at their inner ends on a cross member 5 and are guided by pins 6 and 7. A strip 9 provided with an inverted bead 10 is secured to the cross member 5 and serves to retain the keys from being lifted off the pins 6. Springs 11 bias the keys upwardly, the upward movement of the keys being limited by stops 12 secured in cross member 14 positioned above the keys. The numeral 15 indicates generally a switch which is provided for each key, part being carried by the key, and part 50 by the cross member 14; this switch is opened and closed by movement of the key and will be referred to and described in detail later. A horizontal panel 16 covers the rear portions of the keys, and above this panel is a vertical panel 55 17 which contains the various "stops" 18 for se-

lection of the notes to be played. In this case the stops operate electric switches. Closing the cabinet is a cover 19. The panels 16 and 17 and the cover 19 are hinged to the cabinet to permit easy access to the interior of the organ.

Located in the rear portion of the organ between front panel 20 and rear panel 21 is the reed chest 22. The reeds are wind-operated, and for producing wind pressure any convenient type of blower 23 is provided in the blower box 24 located beneath the reed chest. The blower is run by an electric motor 25 or other suitable means. An opening 26 communicates between the blower box and the reed chest for the admission of the wind from the blower to the reed chest.

The reeds are supported in panels 26 which extend transversely across the reed chest and divide the chest into compartments 27 and 29, the compartment 27 being sealed by the panels 26 which render it air-tight. The reeds, indicated by the reference numeral 30 are inserted in grooves in the sides of cells 31 formed in the panels 26, the cells being individual to the reeds. Strips 33 are inserted over the open ends of the cells between the reeds and the panels 26 to seal these portions of the cells and direct the wind through the reeds. Passages 32 in the panels 26 admit wind pressure to the reeds for sounding them. The passages are opened and closed by valves 34 which are provided with felt sealing members 35 for sealing the passages 32. Each of the valves 34 is controlled by an individual electromagnet 36. The electromagnets are connected in circuit with and controlled by the keys of the keyboard, and, when they are energized, they open the respective valves permitting the wind from the compartment 27 to pass through the passages 32 and sound the reeds. The details of construction and operation of the valves and electromagnets will be referred to later. The chest is closed by a cover 37 which may be provided with suitable mechanism for opening and closing it to control the volume. A tremulant fan 38 is preferably placed in the compartment 29. This may be operated by any convenient small motor.

A plurality of relays 40 in the compartment 27 coat in the circuit between the keys and the electromagnets in the selection of the electromagnets by the keys in a manner to be described presently.

The keyboard has a range of five octaves, beginning and ending in C, or sixty-one keys, and, as shown in Figure 3, is divided into an upper and lower register, though the keys of the two registers are of a continuous range. The upper register contains thirty-two keys and the lower twenty-nine. There are five complete sets of reeds, each set co-extensive in range and comparable in progression of pitch with the keys of the keyboard. One complete set of reeds is embodied in each of the panels 26. These sets are designated in the drawings as B16', C16' M8', V8', and F4'. These designations are characteristic terms concerning organs indicating that the tones are similar to respective pipe-organ tones, as bourdon sixteen feet, cello sixteen feet, melodia eight feet, viola eight feet, and flute four feet.

The division point between the registers of the keyboard is near the center, or between E and F as shown in Figure 3. Those keys in the upper register are indicated by superscripts, as C¹, C², etc., running from the center up, and those in

the lower register by subscripts, as C₁, C₂, etc., running from the center down.

Each of the keys is connected in circuit directly with one each of the five separate sets of reeds, and certain of the keys are connected indirectly, or through relays, with five additional reeds, one from each of the separate sets. With reference to Figure 3, take as an example the key C³, this key has a separate conductor leading to each of the C³ reeds, i. e., to the C³ reed in each set. Figure 2 shows a view from the back of the reed chest, and, accordingly, C³ falls at the left end, and C₃ at the right. Similarly, the reeds to the left of the dividing line in Figure 2 include thirty-two reeds of each set, which correspond to the number of keys in the upper register, and the reeds to the right include twenty-nine, which correspond to the number of keys in the lower register.

The dot-dash rectangles 38 shown in Figure 2 indicate diagrammatically the positions of the various reeds and their individual valves and the electromagnets for operating the valves. This figure also shows the lateral positions of the relays 40 in relation to the reeds.

Reference may now be had to Figure 4 showing the electric circuit connecting the keys and the various reeds. This circuit shows only the C notes, but it will be understood that it is applied in a like manner to the other notes. The numerals 36 indicate diagrammatically the electromagnets for operating the valves 34, indicated similarly in Figure 1. The electromagnets are associated with the sets of reeds as indicated, all 35 in each horizontal row being associated with one set, as B16', C16', etc.

The source of current is the usual line 44, which leads to the rectifier 45. From the rectifier, conductor 46 leads to and is connected to each key 3. On each key 3 is a contact bar 47 adapted, on playing of the key, to contact simultaneously all of the wires 49B, 49C, 49M, 49V, 49F and 49R. Each of these wires, except 49R, leads to one of the various electromagnets 36, then through conductors 50B, 50C, 50M, 50V and 50F, respectively, and switches 51B, 51C, 51M, 51V and 51F, respectively, to return conductor 52 and the rectifier, completing the circuit. The switches 51 are opened and closed by the respective stop levers 18.

In the description following, it will be understood that, when a particular electromagnet is energized, it opens its associated valve and allows the wind pressure to sound the respective reed.

The selection of the notes to be played is accomplished as follows: Assume it is desired to play the bourdon set of reeds in the upper register. The stop lever 18B in the upper register of stops is pressed down closing the switch 51B, and, when the key C¹ is pressed down, the bar 47 contacts all of the wires 49, but particularly wire 49B, closing the circuit through the electromagnet 36B in the C¹ group. The notes associated with a particular key are arranged in a vertical tier with that key, in Figure 4, and are herein designated a "group," as distinguished from a "set" which refers to that series of notes disposed in a horizontal row and which are similar in range to the keyboard. These designations are applicable whether reference is to reeds, valves, or electromagnets. The circuit as thus closed is from conductor 46, to key 3 and bar 47, conductor 49B, electromagnet 36B, conductor 50B, switch 51B and conductor 52. If the key C² is pressed, the circuit is closed through similarly

designated elements energizing the electromagnet 36B in the C² group. The arrangement is the same for all the keys in that register, and, when the bourdon stop is pressed, all of the reeds in the bourdon set associated with the upper register are put in circuit.

A similar procedure is followed for the other sets of reeds. When the stop 18C is pressed and the key C¹ played, the circuit is completed from conductor 46, through key 3 and bar 47, to conductor 49C, to electromagnet 36C in the C¹ group, to conductor 50C, switch 51C and conductor 52. This procedure is followed for the remaining electromagnets, and, since the switches 51 are independently operable, it can be seen that the notes of the various sets can be selected, i. e., any or all.

The notes of any particular group are, of course, not duplicates; they may be either of different pitch or of different timbre, e. g., the B16' and the C16' are of the same pitch while the former assimilates a wind note and the latter a string note. The two 8' notes are one octave higher than the 16' notes, while the 8' notes differ from one another in timbre, and the 4' note is one octave higher than the 8' notes.

The lower register is put in circuit and played precisely as the upper register is. The notes in each set, as B16', C16', etc., being of a continuous range, it follows that if corresponding stops are pressed in both registers, there is a continuous range across the keyboard as in a simple organ. It is likewise possible to put one set in play for one register, and another for the other register, or any combinations for either. Many effects are thus obtainable, as, for instance, a melody may be played on the upper register with accompaniment of a different type on the lower register. Also, a pedal effect may be produced by the lower register.

A full organ stop is indicated at 54. A bar 55 is secured to this stop, and pressing this stop actuates the bar 55 to close all of the switches 51, avoiding the necessity of pressing the individual stops separately. When the stop 54 is actuated, all five sets of notes in both the upper and lower register are put in play.

Another novel feature of the organ is that not only will each key play five notes, but certain of the keys will play five additional notes. Conductor 46a leads from the rectifier to conductors 56 associated with relays 40. Bars 57 connected to the armatures of the relays 40 are in constant contact with conductors 56 and on energization of the relays and actuation of the armatures the bars 57 come into contact also with conductors 59. The circuits through the relays are closed only when the circuits through the stops and keys are closed. When the stops 18B and 18R are pressed and the key C¹ played, not only is the circuit closed through the electromagnet 36B of the C¹ group, but also through the relay 40 in line with that key; when the key C¹ is played, the bar 47 is in contact with the conductor 49R and the circuit is closed from the conductor 46, through key C¹, conductor 49R, relay 40, conductor 50R, switch 51R, to conductor 52. This circuit energizes the relay 40 contacting the bar 57 with the conductors 59 closing the circuit from conductor 46a, through conductors 56, bar 57, conductor 59B, electromagnet 36B in the C² group, conductor 50B, switch 51B, to return conductor 52. Thus, stop 18R in the upper register is the "super octave" stop. When this stop is pressed, the key C¹ will play not only the note in

the C¹ group, but also the note in the C² group in the same set. This follows also for the corresponding notes in the other sets. When, for example, stop 18C is pressed and the C¹ key played, the electromagnet 36C in the C¹ group is energized, the circuit being closed in the manner previously described; and, when the stop 18R is pressed, the relay 40 is energized in the manner just described in connection with the electromagnet 36B. The circuit through the relay is then from conductor 46a, conductors 56 and bar 57, conductor 59C to electromagnet 36C in the C² group, return conductor 50C, through switch 51C to conductor 52. One key cannot play the corresponding notes in the group an octave above its own group unless the latter are also played, since the same switches 51 control the return conductors for both groups.

Obviously, there are no relays associated with keys of the uppermost octave since the relays are for controlling the group of notes an octave higher than those of the group of the particular key. When all of the notes of the key C¹ group are sounded and the stop 18R pressed, all of the notes in the C² group will also be sounded, making it possible to sound as many as ten notes with one key. When both keys C¹ and C² are played, one group of notes will be duplicated in the progression, leaving fifteen notes sounded. It is possible to play as many as fifty notes with one hand, if the keys are not played in octaves, from which it will be seen that great volume is attainable.

The procedure is the same with respect to the lower register, except that the stop 18R in this register is a "sub octave" stop, i. e., it puts in circuit the electromagnets of the group one octave below the key played. Similar to the upper register, there are no relays associated with the lowermost octave of the lower register since the relays of this register are for controlling notes an octave lower than the keys with which they are associated.

Reference to Figure 2 will show the number and positions of the relays 40 with respect to the reeds and electromagnets. Twenty relays 40 are shown in the upper register, one in line with each of the lower twenty electromagnets 36, the uppermost octave, or twelve notes, being without corresponding relays. The scheme is similar in the lower register, there being seventeen relays, one in line with each of the upper seventeen electromagnets 36, leaving the lowermost octave, or twelve notes without corresponding relays.

In Figure 2, the relays 40 as well as the electromagnets 36 are shown schematically in dot-dash lines, those aligned vertically with one another being operable by the same key.

Figures 5 and 6 show in detail the preferred form of switch to be used on the keys. A rod 61 extends the length of the keyboard and is secured by means of spaced brackets 62 to the cross member 9. This rod is connected to conductor 46 in the circuit of Figure 4. A flexible conductor 64 soldered at 65 to the rod 61 leads to each of the keys and is electrically connected to the contact bar 47. Insulation blocks 66 are secured to the cross member 14, one to a key. Conducting wires 49 are clamped between insulation blocks 66 and the cross member 14, with one end extending out in proximity with the contact bar 47 and the other end extending through the insulation block at 67. When the key is pressed down, the contact bar 47 comes into

contact with the conducting wires 49, as shown in dotted lines in Figure 6, completing the circuit through the switch. The wires 49 are flexible, and this assures that all of them will be contacted by the bar 41. The conducting wires 49 lead to various electromagnets and relays of each key as described in connection with Figure 4.

Figures 7, 8, and 9 show in detail the preferred form of stops and the switches operated thereby. Referring to Figures 7 and 8, each switch comprises a block 70 in which are two spring contacts 71 and 72 insulated from one another, and each having a contact point 74. The stop lever 18R is pivoted in the panel 17 on a wire bead 15 extending across all the stops and held in place by means of blocks 16. When the stop is pressed down to the dotted line position, the inner end 71 thereof forces the spring contacts 71 and 72 into contact with each other. All of the spring contacts 71 are contacted by a common contact bar 79, at 80, the bar 79 being connected to the conductor 52 of Figure 4. The ends of the spring contacts 72 are connected with respective conductors 50 as described in connection with Figure 4.

Figure 9 is a view of the switch operated by the full organ stop. A spring contact 81 is secured in each of the blocks 70 in contact with the spring contact 72. Secured to the bar 55 is a spring lever 82 which is actuated by the inner end of the stop lever 54. When the stop lever is pressed down to the dotted line position, the bar 55 is thrown into contact with the spring contacts 81 of all the switches 51. A conductor 84 connects the bar 55 with the common contact bar 79 completing the circuit through the contacts 81 of all of the switches.

The preferred form of electromagnet 36 for operating the valves controlling the wind passages to the reeds is shown in Figure 10. The electromagnet comprises the usual winding 85 and core 86. The individual conductors 49 (and 59) of Figure 4 are connected to the plate 87. A resistor 89 inserted in parallel with each electromagnet serves the dual purpose of preventing objectionable noises in the operation of the electromagnet, and preventing corrosion of the contact points of the switches. Both the winding and resistor are grounded to the plate 90, which serves also to support the electromagnet. One plate 90 is arranged for supporting those electromagnets of each set which correspond to one register of the keyboard, and serves as a common ground therefor, and the plates accordingly are connected to respective conductors 50 of Figure 4. The positions of these plates 90 and the electromagnets supported thereby is shown in Figure 2. This arrangement of supporting a plurality of electromagnets and valves on one plate lends simplicity and economy and aids in aligning the various valves accurately on the panels 26. An armature in the form of a lever 91 is pivoted on the plate 90 with the lower end curved to overlie the core 86. The valve 34 is glued to the lever 91, and upon energization of the electromagnet, the lever 91 is rotated counterclockwise as viewed in the figure, opening the valve. The valve is normally held closed by a tension spring 92 anchored between the upper end of the lever 91 and a lug 94 struck up from the plate 90.

The relay 40 shown in Figure 11 embodies an electromagnet similar to that shown in Figure 10. The individual conductors 49R lead from the keys

to the plates 95, and all of the electromagnets in the relays are grounded to the plate 96 which is connected to respective conductor 50R of Figure 4. These plates 96 are constructed and arranged similarly to the plates 90, each serving as a support and ground for the relays of one register. Their arrangement is shown in Figure 2. Upon energization of the electromagnet, the lever 97 is rotated counterclockwise, drawing the block 99 to the left. The contact bar 57 in the form of a wire loop secured to the block 99 surrounds the upper ends of contact wires 56 and 59. These contact wires are secured in place between insulation blocks 101 and supporting member 102. The lower ends of the contact wires extend through the insulation blocks at 104. The upper ends of the contact wires 56 are bent over and remain in constant contact with the loop 57, and the lower ends extending through the insulation block are soldered to a rod 105 which is connected with the conductor 46a of Figure 4. The contact wires 59 also extend through the insulation blocks and lead to the respective electromagnets as described in connection with Figure 4. When the block 99 is drawn to the left, the loop 57 interconnects the wires 56 and 59 completing the circuit through the relays for operating electromagnets as described in connection with Figure 4.

While I have shown a preferred form of the invention, it is to be understood that various changes in details and rearrangements of parts may be made without departing from the spirit and scope of the appended claims.

I claim:

1. In an electric organ, note sounding devices arranged in sets and groups with the devices of each set of a range of pitches coextensive with the range of the keyboard and the devices of each group of different tonal qualities, magnetically operated valves individual to the respective devices controlling admission of wind thereto, and means comprising set stop switches and key switches for selectively operating the valves of a selected group and optionally operating the corresponding valves of a group an octave of the selected group responsive to actuation of the key corresponding to the selected valve group, said set stop switches and key switches solely controlling selection and operation of the valves.

2. In an electric organ, note sounding devices arranged in sets and groups with the devices of each set of a range of pitches coextensive with the range of the keyboard and the devices of each group of different tonal qualities, magnetically operated valves individual to the respective devices controlling admission of wind thereto, means comprising set stop switches and key switches for selectively operating the valves of a selected group and optionally operating the corresponding valves of a group an octave of the selected group responsive to actuation of the key corresponding to the selected valve group, said set stop switches and key switches solely controlling selection and operation of the valves, and a full organ stop switch for simultaneously closing all of the set stop switches.

3. In an electric reed organ, reeds arranged in sets and groups with the reeds of each set of a range of pitches coextensive with the range of the keyboard and the reeds of each group of different tonal qualities, said groups respectively corresponding to the keys of the keyboard, magnetically operated valves individual to the respective reeds controlling admission of wind

thereto, a set of relay switches respectively corresponding to the keys and connected to the valves of the corresponding groups of valves for operating the latter, and means comprising set stop switches and key switches for selectively operating the valves of a selected group and optionally coupling to corresponding valves of a group an octave of the selected group the relay switch corresponding to the key actuated, responsive to actuation of the key corresponding to the selected valve group, said set stop switches and key switches solely controlling selection and operation of the valves.

4. In an electric reed organ, reeds arranged in sets and groups with the reeds of each set of a range of pitches coextensive with the range of the keyboard and the reeds of each group of different tonal qualities, valves individual to the respective reeds for admitting wind thereto each comprising an actuating coil, a source of electric current, means comprising set stop switches individual to the coils of the respective sets of valves each permanently connected to one side of all the valve coils of the corresponding set and providing the sole means for connecting all of the coils of that set to one side of said source of current, key switches individual to the respective groups of valve coils each comprising separate contact members respectively permanently connected to the other side of the valve coils of the corresponding group and an additional contact member, a set of relay switches each comprising an actuating coil and separate contact members and a contact bar for bridging said contact members when said coil is energized, said contact bar being connected to one side of said source of current and said relay contact members being respectively connected to said other side of the coils of a group, one side of each relay coil being connected to said additional contact of a key switch other than that corresponding to the group of valve coils to which the contacts of that relay switch are connected, and means comprising a relay set stop switch permanently connected to the other side of all of the coils of said set of relay switches and providing the sole means for connecting them to the other side of said current source, each of said key switches comprising a contact bar for bridging the contact members of that switch and connecting them to the other side of said current source upon actuation of the corresponding key.

5. In an electric reed organ, reeds arranged in sets and groups with the reeds of each set of a range of pitches coextensive with the range of the keyboard and the reeds of each group of different tonal qualities, valves individual to the respective reeds, electromagnets individual to the respective valves for actuating them for admitting wind to said reeds, conductors individual to the respective sets of electromagnets each connected to one side of all of the electromagnets of the corresponding set, each of said conductors having a set stop switch therein and being otherwise uninterrupted, key switches corresponding to the respective groups of electromagnets each having a contact member individual to each electromagnet of the corresponding group and an additional contact member, continuous conductors connecting the other side of the respective electromagnets of each group to one of the contact members of the corresponding key switch, a set of relays respectively associated with said groups of reeds each comprising an electromagnet and a relay switch closed thereby, said re-

lay switch comprising contact members individually connected by continuous conductors to said other side of the valve electromagnets of the corresponding group, a conductor connected to one side of all of said relay electromagnets having a stop switch therein and being otherwise uninterrupted, and a continuous conductor connecting the other side of the respective relay electromagnets to said additional contact member of a key switch representing an octave of the group of valve electromagnets corresponding to that relay, said key switch comprising a contact bar for bridging all of the contact members thereof upon actuation of the key.

6. In an electric reed organ, reeds arranged in sets and groups with the reeds of each set of a range of pitches coextensive with the range of the keyboard and the reeds of each group of different tonal qualities, valves individual to the respective reeds, electromagnets individual to the respective valves for actuating them for admitting wind to said reeds, conductors individual to the respective sets of electromagnets each connected to one side of all of the electromagnets of the corresponding set, each of said conductors having a set stop switch therein and being otherwise uninterrupted, key switches corresponding to the respective groups of electromagnets each having a contact member individual to each electromagnet of the corresponding group and an additional contact member, continuous conductors connecting the other side of the respective electromagnets of each group to one of the contact members of the corresponding key switch, a set of relays respectively associated with said groups of reeds each comprising an electromagnet and a relay switch closed thereby, said relay switch comprising contact members individually connected by continuous conductors to said other side of the valve electromagnets of the corresponding group, a conductor connected to one side of all of said relay electromagnets having a stop switch therein and being otherwise uninterrupted, a continuous conductor connecting the other side of the respective relay electromagnets to said additional contact member of a key switch representing an octave of the group of valve electromagnets corresponding to that relay, said key switch comprising a contact bar for bridging all of the contact members thereof upon actuation of the key, and a full organ stop switch for closing the circuit through all of said conductors of said sets of electromagnets.

7. In an electric organ, a wind chest, reed panels closing one side of said chest, sets of reeds respectively mounted on said panels, the latter having passages from the wind chest to the respective reeds, a continuous conducting supporting plate secured to each panel, valve means controlling said passages each comprising a valve member and an actuating electromagnet, the electromagnets of each set of valves being secured to the corresponding supporting plate with one side of the coil of each thereof connected to said plate, the latter supporting said valve means and accurately spacing and positioning them with respect to the passages controlled by the valve members thereof while providing a common conductor for the coils of all of the electromagnets of one set, said reeds being arranged in sets and groups with those of each set of a range of pitches coextensive with the range of the keyboard and those of each group of different tonal qualities, and means comprising said supporting plates and set stop switches and key

switches for selectively operating the valves of a selected group and optionally operating the corresponding valves of a group an octave of the selected group responsive to actuation of the key corresponding to the selected group, said set stop switches and key switches solely controlling selection and operation of the valves.

8. In an electric organ, a wind chest, reed panels closing one side of said chest, sets of reeds respectively mounted on said panels, the latter having passages from the wind chest to the respective reeds, a continuous conducting supporting plate secured to each panel, and valve

means controlling said passages each comprising a valve member and an actuating electromagnet, the electromagnets of each set of valves being secured to the corresponding supporting plate 5 with one side of the coil of each thereof connected to said plate, the latter supporting said valve means and accurately spacing and positioning them with respect to the passages controlled by the valve members thereof while providing a common conductor for the coils of all of the electromagnets of one set.
